[57] CLAIM

The ornamental design for a clock radio, as shown and
described.

DESCRIPTION

FIG. 1 is a top, front and left side perspective view of a
clock radio showing my new design;

FIG. 2 is a left side elevational view thereof;

FIG. 3 is a right side elevational view thereof;

FIG. 4 is a top plan view thereof, shown inverted 180
degrees; and

FIG. 5 is a rear elevational view thereof.

The bottom of the clock radio is plain and unornamented.
